IMPROVED OPTICAL COMBINATION

James Tiburce Felix Conti, Paris, France, assignor to Société pour l'Eclairage Rationnel Sper, Paris, France, a French company

Application December 11, 1934, Serial No. 757,025
In France December 1, 1933

1 Claim. (Cl. 176—34)

The invention has for its object an optical combination which provides a pencil or beam of light to be obtained that is flattened and wider than with prior devices and can be carried into effect by the construction of an incandescent electric lamp.

According to the invention, a reflector is formed by a surface of revolution generated by the rotation about a vertical axis of a suitable curve having two different foci. This reflector is combined with a source of light arranged on an arc of a circle located in the plane containing the foci. In cases where the curve is formed by two branches of a parabola having respectively different focal lengths, the source of light can be arranged between the foci.

The invention thus defined may be carried into effect very simply and economically by a simple incandescent electric lamp having a bulb having two adjacent reflecting surface portions, said portions being of the shape of a part of a surface of revolution generated by a planar curved line of two parabolic portions moving about a common axis of revolution, the two parabolic portions having differing focal distances, combined with a filament arranged on an arc of a circle and placed as has been stated, the part of the bulb containing the source of light being silvered to constitute the reflector. This mode of carrying out the invention enables a true head-lamp to be obtained with a simple incandescent electric lamp.

In order to enable the invention to be better understood, reference will be made to the accompanying drawings, which show, by way of example, how the invention may be carried out.

Figure 1 shows diagrammatically the optical effects in a system according to the invention.

Figure 2 is a transverse section of the light pencil or beam as viewed some distance in front of the lamp.

Figure 3 is an elevation, partly in section, of the lamp according to the invention, and

Figure 4 is a plan view of this lamp taken on the plane of the filament.

In Figure 1, the numerals 2 and 3 indicate the two parabolic branches of the curved line which have generated the reflector shown in section in Figure 1. Each of these two branches of the curved line has its individual focus f^1 or f^2 , the light source being placed between the two foci at 4.

Tracing the path of the light rays emitted by the source 4 and reflected by the part 2 of the reflector, it will be seen that the pencil or beam

of light has two boundary rays a and b , while the second part 3 of the reflector provides the pencil which has the boundary rays a and c . It will therefore be seen that the part of the pencil located between a and b has a light density equal to the sum of those of the pencils which originate from the two parts of the reflector 2 and 3, while the part between b and c is less illuminated.

By suitably selecting the relation of the focal lengths of two parabolic branches of the curved line, as well as the position of the source of light, the form of the light beam, as well as the dimensions and the intensities of illumination of the surfaces ab and bc may be modified.

As shown in Fig. 3, the bulb 1 is formed by the rotation of the two parabola branches 2 and 3 about a vertical axis X—X. These two parabola branches have their foci at f^1 and f^2 respectively.

When the source of light at 4 is located between the two foci f^1 , f^2 , the reflected light rays will all be directed below horizontal planes passing through the different reflecting points of the reflector. As the reflecting surface of the bulb is formed by the rotation of the curved line 2—3, it is evident that the foci will not be points, as is the case in ordinary head-lamps, but circles of foci f^1 and f^2 concentric to the wall 5 of the bulb. The filament 6 will then be arranged on a curved line concentric to the axis of revolution and situated between the two circles of foci f^1 and f^2 . It will be supported, for instance, by three supports 7, 8 and 9 fixed on a foot 10.

The arrangement of the three supports and of the filament permits the same bulb to be mounted either for leading in the current through the central support 8 and connecting the supports 7 and 9 in multiple, which permits a given voltage to be employed, or for leading in the current through the supports 7 and 9 and maintaining the supports 8 insulated, which gives a bulb utilizable for voltages twice as great as with the former multiple connection.

The optical combination thus obtained gives a luminous beam or pencil which is flattened and wider than with certain prior devices and thus has great advantages and permits of numerous applications; for example, a lamp thus constructed and placed on a motor-car will illuminate the road over a great width with the advantage of directing all the light toward the ground and avoiding dazzle.

Also the quantity of light produced by the lamp according to the invention is distributed in an advantageous manner and enables wide

surfaces to be illuminated, which is of great advantage in illuminating, for instance, a platform, by arranging a small number of lamps in the troughs employed in indirect lighting.

5 An optical system of this kind will produce an advantageous oblique illumination of surfaces. Thus, if such a surface is represented by the line *a*, *d*, Fig. 1, it will be seen that the more distant points are illuminated by the more intense part 10 *ab* of the light beam, while the nearer points are illuminated by the weaker part *bc*; the illumination of the surface is thus rendered uniform and rational.

I declare that what I claim is:—

An electric lamp comprising a bulb having two adjacent reflecting surface portions, said portions being of the shape of a part of a surface of revolution generated by a planar curved line of two parabolic portions moving about a common axis of revolution, the two parabolic portions having differing focal distances, and a filament constructed and arranged as the arc of a circle concentric to said axis of revolution and located 10 between said foci. 5
